UNITED STATES PATENT OFFICE.

WILLIAM N. SLEICHER, OF TROY, NEW YORK.

ANCHOR-YOKE FOR NON-SKID CHAINS.

1,367,209.

Specification of Letters Patent.

Patented Feb. 1, 1921.

Application filed April 9, 1920. Serial No. 372,609.

To all whom it may concern:

Be it known that I, WILLIAM N. SLEICHER, a citizen of the United States, residing at Troy, in the county of Rensselaer and State 5 of New York, have invented new and useful Improvements in Anchor-Yokes for Non-Skid Chains, of which the following is a specification.

Reference may be had to the accompanying drawings, and the reference characters marked thereon, which form a part of this specification. Similar characters refer to similar parts in the several figures therein.

This invention relates to the type of non-skid devices employing short cross-chains connected at their ends with anchor-yokes mounted upon a convenient portion of the wheel.

The principal object of the invention is 20 to provide an anchorage for the end-links of the cross-chains to which said links can be readily attached and from which they can be readily intentionally detached, but from which their accidental detachment is 25 practically impossible.

Other objects will appear in connection with the following description.

Figure 1 of the drawings is a view in cross-section of the felly of a wheel with a 30 tire mounted thereupon showing in elevation a cross-chain secured to the wheel by means of my improved anchor-yoke applied to a spoke of the wheel.

Fig. 2 is a view in perspective of the anchor-yoke detached, illustrating the manner in which the anchoring links of the cross-chain are applied to the anchor-posts on the yoke.

Fig. 3 is a plan view of the anchor-yoke. 40 Referring to the drawings wherein the invention is shown in preferred form, 1 is the felly, 2 is a spoke, 3 is the rim, and 4 the shoe of the tire of an automobile wheel.

45 My improved anchor-yoke is preferably made in two parts, 5 and 6, of general semi-circular form adapted to embrace between them one of the spokes, 2, of the wheel and to be clamped thereupon by means of screw-bolts, 7, connecting together ears, 8, on the member, 5, with respective ears, 9, on the member, 6.

50 One of these members, as the member, 6, is formed with a pair of anchor-posts, 10, adapted to receive the respective end-links, 11^a, of a cross-chain, 11.

These anchor-posts extend inwardly on opposite sides of the spokes, 2, and each is formed with two transversely elongated enlargements, 12 and 13, at different distances 60 from its base.

These enlargements are preferably in planes oblique to the axis of the yoke as shown in Fig. 1, and their longitudinal axes are at an angle to each other as shown in 65 Fig. 3.

Each of these anchor-posts is adapted to receive a link, 11^a, which can be applied to the posts by first bringing the longitudinal axis of the link parallel with the longitudinal axis of the outermost enlargement, 12, in which position the link can be passed over the enlargement, 12, and then swinging the link around the post until the longitudinal axis of the link is parallel with the longitudinal axis of the enlargement, 13, in which 70 position the link can be passed over said enlargement, 13.

When the chain, 11, and the end-links, 11^a, assume their normal positions after the end-links have been thus mounted upon the anchor-posts, 10, the chain will be securely retained upon the wheel until intentionally removed by disconnecting the end-links, 11^a, from the anchor-post by a reversal of the 80 several movements by which said links were applied to the anchor-posts. The positions which the end-links are required to take in passing over the respective enlargements, 12 and 13, are unnatural positions in the operation 85 of the chain in use upon the running vehicle, so that accidental escape of the links, 11^a, from the anchor-posts is practically impossible.

The device is rendered even more effective 95 by employing chains with twisted links as shown, as twisted links must be more accurately positioned in passing over the enlargements in planes oblique to the axis of the yoke.

For certain purposes of the invention however, chains having ordinary plain links may be employed, and the enlargements on the anchor-posts may be in any desired plane generally transverse with respect to the 100 anchor-posts.

By the use of my invention very slack cross-chains may be employed without danger of their becoming accidentally detached from the anchor-posts, the use of slack 110 chains being desirable in devices of this kind, because the chain is thereby permitted

freedom to position itself between the tire and the road-bed instead of being held to a substantially definite point on the shoe at all times. With a slack chain the wear is distributed over a greater area of the tire than with a tightly fitting chain.

What I claim as new and desire to secure by Letters Patent is—

1. An anchor-yoke for non-skid chains, having a chain-link-engaging post formed with two transversely elongated enlargements at different distances from its base with their longitudinal axes at an angle to each other.
- 10 2. An anchor-yoke for non-skid chains, having a chain-link-engaging post formed with two enlargements at different distances from its base, said enlargements being in planes oblique to the axis of the yoke and elongated, one in a direction at an angle to the other.
- 15 3. The combination with a non-skid chain; of an anchor-yoke formed with two transversely elongated enlargements at different distances from its base, one adapted 25 to receive a link of the chain in one position of said link, and the other to receive said link when swung around the post to another position.
4. The combination with a non-skid chain 30 having twisted links; of an anchor-yoke formed with two enlargements at different distances from its base, said enlargements being in planes oblique to the axis of the post, and elongated, one in a direction at an 35 angle to the other, requiring a twisted link of said chain to be presented in different angular positions to pass the respective enlargements.

In testimony whereof, I have hereunto set 40
my hand this 6th day of April, 1920.

WILLIAM N. SLEICHER.
